[57] CLAIM

The ornamental design for a motor home body front and rear panel unit exterior surface, as shown and described.

DESCRIPTION

FIG. 1 is a top, front perspective view of a motor home body front and rear panel unit exterior surface showing our new design, it being understood that broken lines are for illustrative purposes only and form no part of the claimed design;

FIG. 2 is an enlarged front elevation view of the front panel exterior surface thereof;

FIG. 3 is an enlarged left side elevation view thereof;

FIG. 4 is an enlarged right side elevation view thereof;

FIG. 5 is an enlarged perspective view of the rear panel exterior surface thereof; and

FIG. 6 is an elevation view of the rear panel of FIG. 5.
